UNITED STATES PATENT OFFICE

137,697

DESIGN FOR A TOY

Robert R. Ryder, Ashland, Ohio

Application December 11, 1943, Serial No. 111,989

Term of patent 3½ years

(Cl. D34—15)

To all whom it may concern:

Be it known that I, Robert R. Ryder, a citizen of the United States, residing at Ashland, in the county of Ashland, State of Ohio, having invented a new, original, and ornamental Design for a Toy, of which the following is a specification, reference being had to the accompanying drawing, forming part thereof.

Fig. 1 is a side view of a toy showing my new design;

Fig. 2 is a top plan view; and

Fig. 3 is a front view thereof.

I claim:

The ornamental design for a toy, as shown.

ROBERT R. RYDER.
